FOOT SUPPORT FOR SHOWER BATHS

Stanley S. Kubik and John Kubik, Los Angeles, Calif.

Application July 3, 1956, Serial No. 595,691

4 Claims. (Cl. 4—146)

This invention relates to a foot support which is adapted for use in a shower bath.

At the present time, a shower bath customarily makes no provision for facilitating washing the feet and legs. It is accordingly necessary for a person taking a shower either to balance on one foot and leg while washing the other or to bend down to the floor to wash these portions of the anatomy. In the case of older persons and those in poor health, both of these procedures are difficult and sometimes result in injury.

It is accordingly an object of our invention to provide a foot support which is adapted to be installed in a shower bath and which provides firm support at the proper height for washing the feet and legs.

In its preferred embodiment, our invention contemplates a device having an elongated body member. A foot supporting plate is mounted at the upper end of the body member and a telescopically mounted T-bar is disposed at the lower end. In use, the bottom of the T-bar bears against one corner of the shower, while the foot supporting plate is disposed horizontally, with one edge bearing against the opposite wall of the shower. The body member and T-bar extend diagonally across the shower, with their telescoping providing adjustability for the size of the shower and the height of the person using the device.

It is a further object of our invention to provide a resilient pad for use on the foot supporting plate which grips the wall and which because of its special design will not hold water on its surface.

Another object of our invention is to provide in an alternative embodiment of our invention a foot supporting plate which is adjustable with respect to the body member to provide greater adjustability of the device.

It is accordingly among the objects of our invention to provide a device of the class described having all of the advantages and benefits of the structure set forth and particularly to provide such a device which can be manufactured in a simple and economical manner for widespread sale at a reasonable low price.

Our invention also comprises such other objects, advantages and capabilities as will later more fully appear and which are inherently possessed by our invention.

While we have shown in the accompanying drawings preferred embodiments of our invention, it should be understood that the same are susceptible of modification and change without departing from the spirit of our invention.

Referring to the drawings,

Fig. 1 is a front elevational view of a preferred embodiment of our invention, with the telescoped portion of the T-bar shown in dotted lines;

Fig. 2 is a side elevational view of the same;

Fig. 3 is an enlarged top plan view of the bed on the foot supporting plate;

Fig. 4 is a sectional view taken on line 4—4 of Fig. 1;

Fig. 5 is a perspective view of the upper end of an alternative embodiment of our invention;

2

Fig. 6 is a side elevational view on a reduced scale of our device in use, with the shower bath shown in section.

A preferred embodiment which has been selected to illustrate our invention comprises a body member 10, which preferably is formed from an elongated piece of metal tubing. Attached to the upper end of body member 10 by a pair of bolts 11 or other suitable fastening means is a foot supporting plate 12. The foot supporting plate 12 preferably comprises a flat rectangular piece of metal.

Telescopically mounted in the hollow lower end of the body member 10 is the upper end 13 of a T-bar 14. The T-bar 14 is also preferably formed of metal tubing, with its diameter being slightly smaller than that of the body member 10. The T-bar 14 has a base 15 which extends transversely to the upper end 13. The entire outer surface of the base 15 is covered with a resilient coating 16 which prevents marring of paint or other surfaces which it may contact and which also improves the gripping quality of the base 15. This resilient coating 16 may be applied by dipping the lower portion of the T-bar 14 into a solution of liquid plastic, rubber or other suitable material which dries to form a resilient coating 16 which extends around the entire outer surface of the base 15 and a short distance upwardly therefrom on the outside of the adjacent lower part of the upper end 13 of T-bar 14.

The lower end of the body member 10 is provided with a pair of aligned circular openings 17. The upper end 13 of the T-bar 14 is provided with a plurality of spaced aligned openings 18 of corresponding size. A pin 19 has a shank which extends through openings 17 and through any pair of openings 18 to hold the T-bar 14 in fixed telescopic relationship to the body member 10. The pin 19 is provided with an enlarged head which facilitates its removal from the openings to adjust the positioning of the T-bar 14.

Mounted on the upper surface of the foot supporting plate 12 is a pad 20, which is slightly larger than plate 12 and which is preferably formed of rubber or other suitable resilient material. The bottom of the pad 20 is suitably attached to the plate 12, while the edges of the pad 20 extend beyond the edges of the plate 12.

The upper surface of the pad 20 is provided with a series of spaced continuous vertical ridges 21, which are interlaced with a series of spaced broken horizontal ridges 22. The outer edge of the pad 20 is provided with a continuous ridge 23, which is broken along one edge by a series of openings 24, which are aligned with the ends of the vertical ridges 21 and which are spaced slightly therefrom.

This pattern is important because it acts to prevent water from accumulating on the pad 20 when our device is in use. In this connection, it will be noted that the ridges actually define a plurality of channels which funnel the water and cause it to flow along the sides of the vertical ridges 21 toward the openings 24.

In use, our device is positioned in a shower in the manner shown in Fig. 6 of the drawings. The base 15 of the T-bar 14 fits within one corner of the shower, with the body member 10 extending diagonally across the shower and the edge of the pad 20 of foot supporting plate 12 bearing against the opposite wall of the shower.

It may be noted that the straight edge of the pad 20 which contacts the wall of the shower is provided with a downwardly directed integral lip 25, as shown in Fig. 2. The lip 25 acts as a cushion to prevent marring the wall of the shower. It also provides a better grip on the wall and increases the range of adjustability of positioning of our device.

With the device in the position described, the user

places his or her foot on the pad 20 of foot supporting plate 12. The plate 12 is firmly supported by the body member 10 and T-bar 14 and will support the foot and leg while they are being washed. It is not necessary for the shower user to balance on one foot or to bend over while washing the feet and legs. As soon as one foot and leg have been washed, the device may be used in the same position or in the opposite position for washing the other foot and leg.

Fig. 5 of the drawings shows an alternative embodiment of our invention in which the foot supporting plate 30 is adjustably mounted with respect to the body member 31. This is accomplished by attaching one half of a hinge 32 to the plate 30, while the other half is attached to the end of the body member 31. The adjacent end of the body member 31 is provided with a pair of aligned openings through which a pin 33 is removably mounted. A pair of brackets 34 are attached to the plate 30 and have a plurality of spaced aligned openings 35. The pin 33 may be removed and the positioning of the plate 30 adjusted with respect to the body member 31. The pin 33 may then be replaced through the openings in body member 31 and any desired pair of openings 35 in the brackets 34.

We claim:

1. In a foot support for removably fitting in a shower bath stall, an elongated body member, a linear base element arranged transversely at one end of said body member and connected thereto, and a plate adapted to support the foot of a shower user rigidly connected to the other end of the body member and disposed in a plane diagonal to the axis of the body member, said element being substantially parallel to the plane of said plate, said foot support being adapted to be positioned so that said

base element engages a side bottom corner of the shower stall and the foot plate is arranged substantially horizontally with its outer edge bearing against a side wall of the stall opposite that corner against which the base element bears, the body member of the foot support being disposed to extend at a diagonal angle in the stall.

5 2. In a foot support as claimed in claim 1, means wherein said base element comprises a T-shaped part having a stem portion telescopically engaging the lower 10 part of said body member and a bar transverse to said stem portion.

3. In a foot support as claimed in claim 1 wherein said foot supporting plate is hingedly connected with the body with means between said plate and said body to 15 adjust the relative inclination between them.

4. In a foot support as claimed in claim 1 wherein a resilient pad is mounted upon the outer face of said foot supporting plate, and a pattern of ridges with breaks formed on said plate so as to prevent water accumulating 20 upon said pad.
